UNITED STATES PATENT OFFICE

ALLEN B. COLEMAN, OF DES MOINES, IOWA

DISPLAY RACK FOR ORNAMENTAL TILES

Application filed August 19, 1929. Serial No. 387,014.

The object of this invention is to provide an improved rack embodying a plurality of pivotally mounted panels, each capable of carrying on each of its faces, an illustrative display of a layout or pattern of ornamental tile such as are used for wall coverings.

A further object of the invention is to provide improved means for removably and pivotally mounting display panels for tile and other similar objects.

Still another object of the invention is to provide improved means whereby a plurality of display panels may be mounted for adjustable positioning for selectively displaying different patterns or layouts.

Another object is to provide improved means whereby objects such as tile may be conveniently mounted on opposite sides of an open frame or panel and be held therein for display purposes.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of a display rack embodying my invention.

Figure 2 is a side elevation of a portion of the rack on an enlarged scale, one of the panel frames being shown with a tile layout mounted therein.

Figure 3 is a vertical section on the line 3—3 of Figure 2, illustrating a display panel with different tile layouts mounted on opposite faces thereof.

Figure 4 is a section through one of the display panels, showing it removed from the rack and in position for supporting the intermediate backing member while the first display of tile is being mounted in one face of the frame.

My invention relates to a convenient means for displaying to customers or prospective customers, a variety of layouts or patterns of ornamental tile from which selections may be made.

The device includes a rectangular supporting frame 10, which is preferably composed of channel beams suitably connected and having their open faces directed outwardly peripherally of the frame. The frame 10 may be supported in upright position by means of cross members 12 and 14 at its ends, and preferably is braced to said cross members by means of inclined braces 16, of any suitable character.

The supporting frame 10 is arranged to pivotally support any desired number of similar display panels. In the accompanying drawing, I have shown five of these display panels and they are indicated generally by the characters A, B, C, D and E.

Each display panel or frame preferably is of rectangular form and composed of T-bars 18. The bars 18 are suitably connected at the corners of the frames and are arranged with their web members 18' directed inwardly toward the center of the frame.

The display frames are pivotally supported in the supporting frame 10 by means of centrally arranged pivots or trunnions 20 and 22 at their lower and upper ends. The trunnions 20 and 22 preferably are composed of bolts which are seated in tapped apertures in the upper and lower T-bars 18 and which extend loosely through bearing openings in the bottom and top members of the frame 10. The upper bolts 22 may be removed by unscrewing them and lifting them out of the frame bars 10, after which the panel frames may be tilted slightly to clear the top of the supporting frame 10 to permit the removal of the lower bolts 20 from their seats, which preferably are slightly enlarged for this purpose.

It will be noted from Figure 3 that a suitable ball bearing assembly 24 is located on the pivot bolt 20 below each of the panel frames to facilitate rotary movement thereof.

Each panel frame A, B, C, D and E is adapted to receive on each of its faces, a different display of tile such as 26 and 28 and it is to be understood that the patterns displayed by the respective panel frames may all be different and may be selectively arranged in any desired fashion.

In preparing a display panel or frame for display purposes it is removed from the supporting frame 10 and laid upon a flat surface such as a floor or table.

5 A core or backing member 30 is mounted within and substantially fills the rectangular space defined by the inner margins of the webs 18' of the frame members 18, as clearly shown in Figure 4. This core or backing member may be of any suitable light weight material such as wall board and it is at first supported in the desired position by means of a dummy filler block or sheet 32, which is laid on the supporting surface as illustrated 10 in Figure 4, within the lower face of the panel frame.

Thereafter, a tile display such as 26 is placed in the uppermost face of the display frame and is supported by the core or backing sheet 30 and by the web members 18' of the frame. The tiles preferably are held in place by the use of a suitable soluble cementitious substance such as waterglass or sodium silicate designated at 34.

25 When the first display 26 has been cemented in place, the display frame such as A may be inverted upon the support. The dummy backing plate 32 is then removed and another tile display such as 28 is cemented 30 into the opposite face of the frame in a similar manner. Some of the tiles on each side of the frame overlap the joints between the backing sheet 30 and the web 18' of the T-bars in order to hold the displays securely in place 35 in the frame.

The frame is then mounted in the supporting frame 10 by means of the trunnion bolts 20 and 22 and is ready for use.

It will be noted from Figure 1, that the 40 length of the supporting frame 10 may be considerably less than the combined width of the respective display frames A, B, C, D and E, thereby conserving space. As shown, the total length of the supporting frame may 45 be such that approximately one-half of the panel frames may be arranged in alignment with the supporting frame, as indicated by the display frames C and E, while alternate display frames are arranged transversely, as 50 illustrated by the display frame D. Also, that any individual frames may be arranged at desired angles for display purposes, as indicated by the positions of the frames A and B.

55 It is obvious that any one of the display frames may be arranged with either face directed toward the observer, while all of the remaining frames are arranged edgewise or 60 transversely, so that the attention of the observer may be directed to a single panel. Also, that all of the frames may be simultaneously arranged at the same angle, such for instance as indicated by the position of the 65 frame A or B, so that portions of the dis-

plays carried by each display frame may be viewed simultaneously.

This provides a very compact and convenient method for displaying either simultaneously or individually, a considerable number 70 of tile patterns for the convenience of the salesman and the customer.

By using a soluble cement such as waterglass, it is an easy matter to remove a display 75 from the display panel and substitute another when occasion may require.

I claim as my invention:

1. In a display device for tile, a rectangular frame formed of T-bars having their webs directed inwardly of the frame, a backing sheet occupying the space defined by the inner margins of said webs, and tile displays mounted in both faces of the frame, the tile units being mounted against and cemented to the backing sheet and webs of the T-bars, 80 some of the tiles of the displays being arranged to overlap the joints between said webs and the backing sheet.

2. In a display rack for tile and the like, a vertically disposed rectangular supporting frame formed of channel bars arranged with their open faces directed outwardly of the frame, a plurality of display frames each having pivots at its upper and lower ends, 90 said supporting frame being formed with openings in its top and bottom horizontal members to receive said pivots, whereby the projecting ends of the pivots are concealed within the channel bars.

3. In a display rack for tile and the like, a vertically disposed rectangular supporting frame, a display frame adapted to carry removable tile displays, a pivot member projecting from one horizontal member of said display frame loosely through the corresponding member of the supporting frame, and a threaded pivot member adapted to be extended loosely through the opposite horizontal member of the supporting frame and to be removably seated in the corresponding horizontal member of the display frame, for removably pivotally mounting the display frame in the supporting frame.

Des Moines, Iowa. August 9, 1929.
